VERTICALLY-ADJUSTABLE TABLE

Earl L. Page, Nashville, Ind.

Application July 6, 1950, Serial No. 172,251

5 Claims. (Cl. 311—39)

1 This invention relates to improvements in tables, primarily adjustable tables for use in homes and more particularly in the living room.

One of the problems in present day small houses and apartments is that of having adequate furniture specifically suitable for the many functions for which the average family would like to make provision. Among the items of furniture that are almost universally standard for the modern home, next to the tables required for meals, are the coffee, cocktail, or "occasional" table for use in front of the davenport or lounge and the card table. In such small abodes as presently are being constructed for the average family, space is at a premium for either the use or the storage of furniture that is needed to meet the day to day requirements. Accordingly, many homes attempting to expand beyond the essential needs have to cramp their living quarters or overload their storage space.

The main objects of this invention, therefore, are to provide an improved form of table normally adapted for use as a low-level coffee, cocktail, or "occasional" table but which is easily convertible into a form suitable for use as a card table or the like; and to provide an improved table structure of this kind which is economical to manufacture, simple to operate, and which in its collapsed low-level position is as attractive as any comparable conventional living room furniture.

In the particular embodiment of the invention shown in the accompanying drawings:

Figure 1 is a top perspective view of a table constructed in accordance with this invention shown in its collapsed form for normal use.

Fig. 2 is an under perspective view of the same.

Fig. 3 is a view similar to Fig. 2 but showing the table top in the process of being extended or contracted with respect to the base.

Fig. 4 is a similar view of the table in its fully extended form.

Fig. 5 is an enlarged plan view of the under side of the table top shown in the foregoing figures.

Fig. 6 is a view similar to Fig. 1 but showing the table top as being square instead of round.

Fig. 7 is an enlarged fragmentary detail of one of the legs and leg extensions in their relatively extended positions, as viewed from the plane of the line 7—7 of Fig. 4.

Fig. 8 is an enlarged fragmentary cross sectional view of the table in its collapsed form as shown in Fig. 1, the view being taken on the plane of the line 8—8 of Fig. 1.

Fig. 9 is an enlarged fragmentary perspective view of the hinge connection of one of the leg and leg extension showing the spring which normally urges the extension toward its elevated or extended position.

2 An improved adjustable table embodying this invention comprises a base 11, and a top 12, the legs 13 of which base 11 have extensions 14 hinged thereto and connected to cam-track followers 15 travelling in cam tracks 16 formed in the under side of the top 12 whereby a rotation of the top 12 relative to the base 11 disposes said top at either of two different levels with respect to said base, as clearly shown in Figs. 1, 2, and 4.

The base 11 is of more or less conventional construction wherein the legs 13 are supported at the ends of cross braces 17. Although herein shown a rectangular cross section, the legs 13 and the cross braces 17 could be of any other desired cross sectional form, as taste might dictate. A center hollow post or pedestal 18 preferably is arranged at the intersection of the cross braces 17. A shaft 19 is secured to the table top 12 and slidably and rotatably mounted in the hollow post 18.

The table top 12 may be of any desired contour—circular or square as herein shown, or oval. It may be constructed in the conventional manner, preferably with a rim 20 depending from the perimeter of the top 12 and thereby forming a cavity 21 on the under side of the top. A sub-top 22 coextensive with the table top 12 is secured to the under face of the rim 20 so as to inclose the cavity 21 to provide a chamber wherein the upper portion of the cam-track followers 15 are housed. The subtop 22 may be of any suitable material such as plywood or pressed fibre board. The cam tracks 16 are cut in the subtop 22, extending spirally outward from a point near the center in the form of arcs, to a point near the perimeter (see Fig. 5).

40 The leg extensions 14 are each provided with mount brackets 23 and 24 oppositely curved and located at the opposite ends of the extensions and hinged to the legs 13 and the cam-track followers 15 by pivot pins 25 and 26 respectively.

45 Each leg extension 14, and the companion leg 13 are cut away at 27 and 28 (see Fig. 9) to provide a recess for a tension spring 29 embracing hinge pin 25. The ends of spring 29 bear against the extension 14 and the leg 13 so as to normally urge the extension 14 toward its elevated or extended position, as shown in Figs. 4 and 7. It should be observed that the vertical axis of the pivot pins 25—26 are not in alignment with the

50 vertical axis of the leg extension 14. (See Fig. 7).

The cam-track followers 15, as herein shown, each comprises a pair of blocks 30 and 31 secured together on opposite sides of the subtop 22 by a screw pin 32 which extends through the cam-track slots 16.

A table embodying this invention is designed for use generally as a cocktail, coffee, or "occasional" table in front of a living room davenport or lounge. When so used the top 12 would be disposed at its lower level, resting on the upper ends of legs 13 with the extensions folded inwardly and horizontally under the top 12 (see Figs. 2 and 8). So arranged, the top 12 is too low to be used for instance, as a card table. However, the table top 12 may be conveniently and easily shifted to a higher level so as to make the table available for such use. This conversion is easily effected by a person grasping the perimeter of the table top 12 at two points and giving the table top 12 a rotative movement in a clockwise direction, as it is lifted. This movement of the table top relative to the base 11 will cause the pins 32 in the cam-track followers 15 to follow the cam-track grooves 16 in a lateral direction thereby allowing the springs 29 to urge the leg extensions 14 to the vertical positions shown in Figs. 4 and 7.

When it is desired to reconvert the table to its normal use it is only necessary to reverse the rotation of the top 12 and press downwardly that is, rotate the top in a counterclockwise direction so as to cause the cam-track follower pins 32 in the cam-track groove 16 to move inwardly towards the center of the table. This will effect a swing of the leg extensions 14 inwardly and downwardly against the action of the springs 29 allowing the top to come to rest at its lower level on the legs 12, as shown in Figs. 1 and 6.

Other variations and modifications in the details of structure and arrangement of the parts may be resorted to within the spirit and the coverage of the following claims:

I claim:

1. A table of the class described comprising a supporting base, a top mounted for axial shifting on said base, substantially spirally extending cam tracks formed on the under side of said top, cam-track followers slidable on said tracks, and a plurality of links hinged to said base and to said followers whereby said top may be disposed at vertically different levels with respect to said base.
2. A table of the class described comprising a supporting base, a top rotatably mounted on said base, arcuate-shaped, substantially spirally extending cam tracks, a plurality of links hinged to said base and to said followers for shifting between horizontal and vertical positions whereby

rotative movement of said top disposes the same at vertically different levels, and means yieldingly urging said links into their vertical positions.

3. A table of the class described comprising a supporting base mounting a plurality of spaced vertical legs and a central post, a top mounted for axially shifting on said post, substantially spirally extending cam tracks formed on the under face of said top, cam-track followers slidable on said tracks, link extensions hinged one to each of said legs and to one of said followers whereby said top may be disposed at vertically different levels with respect to said base, and yielding means for holding said top in the upper of said levels.

4. A table of the class described comprising a supporting base mounting a plurality of spaced vertical legs and a central post, a top rotatably mounted on said post, a plurality of arcuate-shaped substantially spirally extending cam tracks formed on the under face of said top, and link extensions hinged one to each of said legs and to one of said followers whereby rotative movement of said top disposes the same at vertically different levels with respect to said base.

5. A table of the class described comprising a supporting base, a top formed with a perimetrical rim depending therefrom, a subtop substantially coextensive with said top secured to the under face of said rim and having substantially spirally extending cam grooves formed therein, blocks suspended from said subtop and each having a pin to traverse one of said grooves, and links hinged to said base and to said blocks whereby the shifting of said block pins in said grooves disposes said top at vertically different levels with respect to said base.
